US00D896979S

(12) **United States Design Patent** (10) Patent No.: **US D896,979 S**
(45) Date of Patent: **** Sep. 22, 2020**

(54) **COMBINED DRYER AND SANITIZER FOR RECHARGEABLE ELECTRONIC DEVICES**

(71) Applicant: **Ear Technology Corporation**, Johnson City, TN (US)

(72) Inventor: **Daniel R. Schumaier**, Elizabethton, TN (US)

(73) Assignee: **Ear Technology Corporation**, Johnson City, TN (US)

(**) Term: **15 Years**

(21) Appl. No.: **29/722,226**

(22) Filed: **Jan. 28, 2020**

(57) **CLAIM**

The ornamental design for a combined dryer and sanitizer for rechargeable electronic devices, as shown and described.

DESCRIPTION

FIG. 1 is a top perspective view of a combined dryer and sanitizer for rechargeable electronic devices showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of the combined dryer and sanitizer for rechargeable electronic devices of FIG. 1, with an open lid.

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines depict portions of the combined dryer and sanitizer for rechargeable electronic devices that form no part of the claimed design; the broken lines form no part of the claimed design.

1 Claim, 12 Drawing Sheets
